W. COLCLOUGH

SHOCK ABSORBER FOR GARMENT PRESSES

Filed Dec. 16, 1920

FIG. 1.

FIG. 4.

INVENTOR

William Colclough
Brockett & Hyde

ATTORNEY.

Patented July 7, 1925.

UNITED STATES PATENT OFFICE.

WILLIAM COLCLOUGH, OF NORWOOD, OHIO, ASSIGNOR, BY DIRECT AND MESNE ASSIGNMENTS, OF ONE-HALF TO THE AMERICAN LAUNDRY MACHINERY COMPANY, OF NORWOOD, OHIO, A CORPORATION OF OHIO, AND ONE-HALF TO METROPOLITAN TRUST COMPANY, OF NEW YORK, N. Y., A CORPORATION OF NEW YORK, TRUSTEE.

SHOCK ABSORBER FOR GARMENT PRESSES.

Application filed December 16, 1920. Serial No. 431,169.

To all whom it may concern:

Be it known that I, WILLIAM COLCLOUGH, a citizen of the United States, residing at Norwood, in the county of Hamilton and 5 State of Ohio, have invented certain new and useful Improvements in Shock Absorbers for Garment Presses, of which the following is a specification.

This invention relates to cushioning devices for garment pressing machines. The 10 object of the invention is to provide an improved cushioning device for relieving the shock ordinarily produced when the operating parts of the mechanism move toward 15 open or released position, and particularly such a device which is automatic in operation, simple in construction, which can be readily applied to forms of presses now in use, and which does not interfere with or 20 complicate other parts of the mechanism.

Other objects of the invention will appear from the following description and claims when considered together with the accompanying drawings.

25 Fig. 1 is a side elevation of the garment press with parts broken away to show the shock absorber; Fig. 2 is a horizontal section in the plane of line 2—2 of Fig. 1; Fig. 3 is a rear elevation of the shock absorber, 30 with part of the frame of the press broken away; and Fig. 4 is a vertical longitudinal section of a portion of the shock absorber in the plane of line 4—4 of Figs. 2 and 3.

Although capable of application to other 35 presses, it is here shown in connection with the type of press disclosed in the application of William E. Andree, Serial No. 336,575, filed November 8, 1919.

The main frame 1 supports the pedestal 40 2 upon which is supported the buck or lower press member 3. The upper press member 4 is carried upon the end of the lever arm 5 pivotally mounted at 6 upon the bracket arm 7 of the frame. The lever arm 5 is connected 45 at the pivot point 8 with the operating arm 9 which in turn has pivotal connection at 10 with one end of the toggle lever mechanism comprising the links 11 and 12. These links are pivotally connected at 13, while the link 50 member 12 forms one end of a bell crank lever which is pivotally mounted at 14 upon the frame and whose other end 15 has pivotal connection with the upwardly extending

connecting rod 16. The rod 16 is pivotally connected at its lower end, as at 17, to the 55 treadle lever 18, which in turn is rockably mounted upon the shaft 19 in the frame. A spring 20 whose ends are connected to the lever arm 5 and the base of the frame, respectively, as indicated in the drawings, normally tends to raise the upper press member 60 away from the buck. The type of machine thus far described as already known in the art and it will be readily understood that upon pressing treadle 21 the upper press 65 member 4 will be lowered by the straightening of the toggle lever against the tension of spring 20; and in order to release the upper press member pressure is applied to the release treadle 22, whereupon the press 70 is opened by the force of the spring 20.

In order to overcome the shock to the mechanism caused by the sudden and forceful opening of the press by the spring 20, I 75 have provided the following means for absorbing such shock and for insuring a quiet and gradual decrease in the speed of the upper press member during its opening operation until it comes to a full stop.

The bracket 23 is detachably mounted 80 upon the base portion of the frame indicated at 24 by means of the conical pointed set screws 25. Upon the bracket 23 there is pivotally mounted at 26 the shock lever 27 which is provided at its free end with a 85 longitudinal slot 28 through which extends the stud 29. This stud 29 has screw thread engagement with the collar 30 on the shaft 19, pin 29 providing a detachable lock for these two parts. Stud 29 is surrounded by 90 the coil spring 31 which abuts at one end against the disk 32 bearing against the shock lever 27 and at its other end against the disk 33. Slot 28 allows proper play between lever 27 and stud 29. By means of the nuts 34 on the stud 29 the tension of the spring can be regulated, and hence the degree of compression is predetermined according to 95 conditions. The degree of opening of the press is also controlled by this means. A web portion 35 extends between the arms of the treadle lever 18 and is adapted during 100 opening movement of the press to contact the under face of the shock lever 27 and in this way to cause actuation of the shock absorbing mechanism; that is to say, upon actua- 105

tion of the release treadle 22 main treadle 18 will rise by force of the spring 20, whereupon the shock lever 27 when actuated by the web portion 35 will cause compression of the spring 31.

It is thought that the operation of the above described mechanism and the advantages flowing therefrom will be apparent. Notably among the advantages is that which resides in the fact that the shock absorbing means here described is detachable and can be applied to garment presses now in use. Furthermore, the mechanism involved in my shock absorbing device is of a simple nature and hence not costly to manufacture and yet at the same time highly efficient in its operation and not apt to get out of order in the use for which intended.

What I claim is:

- 20 1. A garment press comprising a frame, pressing members upon said frame, a lever having a portion extending substantially horizontally for operating said pressing members, and a cushioning device readily detachably mounted adjacent the pivot of said lever and lying in the path of movement of said horizontally extending portion of the lever so as to be actuated thereby and adapted to relieve the shock during the opening movement of the press.
- 25 2. A garment press comprising a frame, pressing members upon said frame, a lever for operating said pressing members, a shaft therefor, cushioning means detachably mounted upon said frame, and bearing upon said shaft, and means carried by said lever for actuating said cushioning means during the opening movement of the press.
- 30 3. A garment press comprising a frame, pressing members upon said frame, means for operating said pressing members including a pivoted lever, compression means mounted at the pivot of said lever, a shock lever pivotally mounted on said frame and being adapted to actuate said compression means, and means carried by said first named lever adapted to actuate said shock lever during opening movement of said press.
- 35 4. In a garment press, a cushioning device including a bracket having means for attachment to a pressing machine, a shock lever pivoted upon said bracket, and a compression means adapted for readily detachable connection to the machine, said shock lever being adapted to be actuated by the press operating means and to actuate said compression means during the opening movement of the press.

5. In a garment press, a cushioning device including a bracket having means for attachment to a pressing machine, a shock lever pivoted upon said bracket and having an opening therein, and a compression means adapted for detachable connection through the opening of said shock lever and to the machine, said shock lever being adapted to be actuated by the press operating means and to actuate said compression means during the opening movement of the press.

6. In a garment press embodying a frame, 70 pressing members and operating means therefor, a cushioning device including a bracket having means for attachment to the frame, a shock lever pivoted upon said bracket, and a compression means adapted 75 for detachable mounting upon a part of the press operating means, said shock lever being adapted to be actuated by the press operating means and to actuate said compression means during the opening movement 80 of the press.

7. A garment press comprising a frame, pressing members upon said frame, a lever for operating said pressing members, a cushioning device mounted adjacent the pivot of 85 said lever and lying in the path of movement of said lever so as to be actuated thereby, said cushioning device being adapted to relieve the shock during the opening movement 90 of the press.

8. A garment press comprising a frame, pressing members upon said frame, lever mechanism including a treadle for operating said pressing members, and a cushioning device mounted adjacent the pivot of said 95 treadle and lying in the path of movement of said treadle so as to be actuated thereby, said cushioning device being adapted to relieve the shock during the opening movement 100 of the press.

9. A garment press comprising a frame, pressing members upon said frame, means for operating said pressing members including a pivoted lever, compression means, a shock lever pivotally mounted on said frame 105 and adapted to actuate said compression means, said first named pivoted lever being adapted to engage said shock lever adjacent the pivot of the former so as to effect the actuation of the compression means by said 110 shock lever and thereby relieve the shock during the opening movement of the press.

In testimony whereof I hereby affix my signature.

WILLIAM COLCLOUGH.
